(57) **CLAIM**

The ornamental design of a display screen with transitional graphical user interface, as shown and described.

DESCRIPTION

FIG. 1 is a front view of a first image in a sequence of a transitional graphical user interface on a display screen; FIG. 2 is a front view of a second image in the sequence of the transitional graphical user interface on the display screen;

FIG. 3 is a front view of a third image in the sequence of the transitional graphical user interface on the display screen; FIG. 4 is a front view of a fourth image in the sequence of the transitional graphical user interface on the display screen;

FIG. 5 is a front view of a fifth image in the sequence of the transitional graphical user interface on the display screen; and,

FIG. 6 is a front view of a sixth image in the sequence of the transitional graphical user interface on the display screen. The appearance of the transitional graphical user interface of the embodiment sequentially transitions between the images shown in FIGS. 1-6. The process or period in which one image transitions to another image forms no part of the claimed design. The broken line at the periphery of the figures illustrates the display screen, and the remaining broken lines illustrate portions of the transitional graphical user interface. None of the broken lines form part of the claimed design.
